UNITED STATES PATENT OFFICE

2,350,784

AIR CHARGE COOLING DEVICE

Kurt Löhner and Peter Kappus, Munich, Germany; vested in the Alien Property Custodian

Application September 26, 1939, Serial No. 296,654
In Germany September 23, 1938

9 Claims. (Cl. 123—119)

This invention relates to a cooling device for the charging air for air-cooled radial engines especially double-row radial engines with the blower arranged in front of the cylinders.

It is well known that by precompressing the air in the blower the temperature of the charging air is raised to such a degree as to have a deleterious influence upon the working conditions. In the constructions heretofore known the charging air was made to flow through coolers interposed between the blower which is then arranged behind the cylinders and the corresponding cylinder.

An object of the present invention as above mentioned is to arrange the cooling device with the blower arranged in front of the cylinders in a manner differing considerably from the constructions already known.

According to the present invention there is provided around the periphery of the blower an annular cooler which may be subdivided into single coolers, in which case the intermediate spaces between two neighboring coolers may be provided with baffles. The annular cooler or the single coolers may be formed with tubes arranged radially or parallel or approximately parallel relatively to each other which tubes in order to obtain a great surface and a more efficient transfer of heat are given a great length relatively to their width. To further increase the cooling effect the tubes are connected externally by means of spaced-plates or ribs arranged normal to the tubes. To stiffen the tubes and to further increase the heat transfer from the charging air to the plates or ribs and finally to the cooling air the tubes according to the present invention are subdivided by walls into a plurality of conduits.

A further advantage of the present construction consists in the fact that a certain number of all cylinders have a common cooler which causes the charging air for more cylinders to flow at first through the tubes of the coolers, which are located in a plane extending more or less vertically with relation to longitudinal axis of the engine and terminate on a level with the cylinder heads, after which the charging air is deflected about 90° by means of guide plates and only then is distributed to the suction pipes leading to the several cylinders.

Further details and advantages will be understood from the following description.

The invention is diagrammatically illustrated by way of example in the accompanying drawings, wherein:

Fig. 1 is a longitudinal sectional view, with parts shown in elevation, of a radial engine adapted for aircraft use and equipped with my improved cooling device.

5 Figs. 2 and 3 are vertical cross sections taken substantially on the lines A—A and B—B of Fig. 1, looking in the direction of the arrows.

10 Fig. 4 is a vertical cross section similar to Fig. 3 showing an alternative arrangement of the cooling device; and

Fig. 5 is a horizontal detail section through the cooler.

15 In the drawings the reference numeral 1 designates an aeroplane propeller and 2 a radial engine mounted to rotate the propeller. A super-charge blower 3 is positioned in front of the engine 2 for rotation by the propeller shaft, and our improved cooler is arranged to cool the compressed air as it passes from the blower 4 toward the engine 2. A ring shaped connecting conduit 5 is provided with air-direct baffles 6 and directs the cooled air through pipes 7 leading to the several engine cylinders. The cooling air is guided to and through the cooler 4 by a suitable 20 formation of the cowling 8, 9; the cooler 4 comprises a series of radial conduits or canals 12 carrying the compressed air and joined together by circumferential series of cooling ribs 11 (note Fig. 3). The inner extremities of the radial conduits 12 open into the peripheral outlet portion of the blower 3, and the outer extremities of the radial conduits 12 open into the ring shaped connecting conduit 5.

25 In Fig. 4 is shown an alternative arrangement wherein the radial conduits 12 are positioned parallel with each other in circumferentially spaced cooling sections, which are separated from each other by baffles 10 which are positioned to divert incoming air through the cooler sections.

30 In Fig. 5 is shown a modified construction whereby the conduits 12 may be strengthened by internal spaced air-guiding ribs 13.

35 The course of the cooling air through the cooler 4 and to the engine cylinders 2 is illustrated by horizontal arrows in Fig. 1 and the course of the air directed to the blower 3 is shown by the downward angling arrow in Fig. 1.

We claim:

1. In an internal combustion engine having a plurality of radially positioned cylinders, in combination, a supercharger mounted co-axially in front of and drivably connected to said engine, and means for guiding and cooling the air delivered by said supercharger to the cylinders of said engine, said means being mounted over the

entire front of the radially positioned cylinders and provided with a plurality of compressed air passages leading from said supercharger to said cylinders, and a plurality of longitudinal air-cooling passages open at and leading from the front of said means to the rear of said means, exiting against said cylinders, said compressed air passages being positioned in heat-conducting relationship to said cooling air passages, whereby all of the air which would otherwise be blown upon the engine must first pass through said means to cool the compressed air.

2. The combination according to claim 1, in which said air-guiding and cooling means comprises an annular radiator having a plurality of radial passages leading from said supercharger to the cylinders of said engine, and a plurality of longitudinal passages extending through the radiator in heat-conducting relationship to said radial passages.

3. The combination according to claim 1, in which said air-guiding and cooling means comprises a plurality of guiding and cooling units connected to and leading from the supercharger at one end, means interconnecting the other ends of said units with one another, means leading from said interconnecting means to each cylinder, each unit including a plurality of substantially parallel passages leading from said supercharger to said interconnecting means and plurality of longitudinal passages extending through said unit in heat-conducting relationship to said parallel passages, and baffle means positioned between and taking up the entire space between individual units for directing all of the oncoming air therethrough.

4. In an internal combustion engine having one or more cylinders, in combination, a supercharger mounted in front of and drivably connected to said engine, and means for guiding and cooling the air delivered by said supercharger to the cylinders of said engine, comprising a radiator mounted over the entire front of said cylinders,

5 having a plurality of parallel passages leading from said supercharger to said cylinders and a plurality of longitudinal passages extending through said radiator in heat-conducting relationship to said parallel passages.

10 5. The combination according to claim 1, in combination with a plurality of strengthening walls positioned in and extending through the passages leading from the supercharger, subdividing each passage into a number of conduits.

15 6. The combination according to claim 4, in combination with a plurality of strengthening walls positioned in and extending through the passages leading from the supercharger, subdividing each passage into a number of conduits.

20 7. The combination according to claim 1, in which said air-guiding and cooling means comprises an annular radiator mounted about the periphery of said supercharger, having a plurality of radial passages leading from said supercharger to the cylinders of said engine, and a plurality of longitudinal passages extending through the radiator in heat-conducting relationship to said radial passages.

25 8. In an internal combustion engine having one or more cylinders, in combination, a supercharger mounted in front of and drivably connected to said engine, and means for guiding and cooling the air delivered by said supercharger to the cylinders of said engine, including a radiator mounted over the entire front of said cylinders, whereby all of the air which would otherwise be blown upon the engine must first pass through said radiator to cool the compressed air.

30 9. The combination according to claim 1, in combination with common means for interconnecting the outer ends of the passages leading from said supercharger, and conduits leading from said common means to the individual cylinders.

KURT LÖHNER.
PETER KAPPUS.
